UNITED STATES PATENT OFFICE.

JOHN T. ALLMAND, OF DETROIT, MICHIGAN, ASSIGNOR TO FISHER CLOSED BODY COMPANY, OF DETROIT, MICHIGAN, A CORPORATION OF MICHIGAN.

LATCH-OPERATING DEVICE.

1,171,690.

Specification of Letters Patent. Patented Feb. 15, 1916.

Application filed September 20, 1915. Serial No. 51,526.

To all whom it may concern:

Be it known that I, JOHN T. ALLMAND, a citizen of the United States, residing at Detroit, county of Wayne, State of Michigan, 5 have invented a certain new and useful Improvement in Latch-Operating Devices, and declare the following to be a full, clear, and exact description of the same, such as will enable others skilled in the art to which it 10 pertains to make and use the same, reference being had to the accompanying drawings, which form a part of this specification.

This invention relates to a latch opening device for use on a removable top for convertible automobile bodies.

It comprises a device adapted to be carried by the upper section of the two-section door when the top is in place. The device is so constructed that it can be easily operated 20 from the inside or from without to swing the ordinary inside latch lever on the lower body section, and it is so arranged that it affords a non-rattling connection with the said latch lever. This will more fully appear in the 25 description following.

In the drawings, Figure 1 is an inside view of portions of the upper and lower door sections of a convertible body when the removable top is in position, and showing 30 my device. Fig. 2 is a vertical section of the same. Fig. 3 is a section on the line A—A of Fig. 2.

a designates the ordinary door used in an open body, *b* the concealed latch casing, *c* 35 the latch lever which protrudes through the segmental slot *d*.

The door section of the removable top is lettered *e* and will be referred to as the upper door section.

40 *f* represents a small casting or sleeve which can be secured to the outside of the door and which acts as one of the bearings for the arbor *g* which passes through the upper door section. To the outside end of this arbor 45 is tightly fitted or soldered a handle *h* which for convenience of reference will be termed the exterior handle. The extension of this handle which fits over the outside end of the arbor *g* is really the member which 50 is rotatably supported by the casting or sleeve *f* to give the arbor *g* a bearing in this sleeve. The extreme inner end of the arbor *g* is screw-threaded and the succeeding portion of the arbor is squared. On the squared 55 portion fits the bushing *i* which may be sol-

dered in place if desired, and also the lever *j*, which is preferably a two-arm lever, one arm above and one arm below the point of attachment to the arbor. A casting or sleeve *k* screws to the inside of the door section *e* 60 and serves as a bearing for the bushing *i*. A cap nut *l* runs on the threads of the inner end of the arbor and together with the washer *m* holds the lever *j* to the inner end of the arbor. The lower arm of the lever *j* 65 is provided near its lower end with a perforation through which may be crowded the rivet-shaped rubber button *n*. One head of this button engages against the latch lever *c*. The other head engages against the angle 70 iron stop *o* when the lever is not being operated. The stop *o* is secured to the top of the lower door section.

A spring (not shown) which customarily keeps the latch proper projected also serves 75 to keep the latch lever *c* in its forward position. This is the common construction of latches for automobile doors and needs no further illustration or description. When the latch is not being retracted, the lower 80 end of the lower arm of the lever *j* is pinched between the top of the latch lever *c* and the stop *o*, and the rubber button *n* is the portion of this arm which is in contact with both the latch lever and the stop. Consequently 85 this produces a non-rattling device, as the force of the spring of the latch which keeps the latch lever in its forward position, is sufficient to hold the latch lever and the lower arm of the lever *j* tightly against the 90 stop *o*. This is important in automobile construction for it is desirable that none of the parts of the body be capable of rattling.

When the top of the body is removed, all 95 parts of my improved device are removed with the upper door section without any necessary disassembling with the exception of the stop *o*; which if in the way of the operation of the latch lever, can easily be taken off by taking out the two screws. 100

It is apparent that with the inside latch lever, which is the prevailing lever now used in the present form of open body construction, it will be impossible to open the door when the top section is in place. Consequently 105 my device accomplishes this purpose, and as already set out in detail, the stop used in conjunction with the lower arm for the lever *j* and the spring-actuated latch lever secures a non-rattling connection be- 110

tween my device and the ordinary inside latch lever. The upper arm of the lever *j* serves as a convenient handle to the operation of the latch lever from the inside, which 5 otherwise would be rather inconvenient with the latch opening device of the upper section in operative connection with the latch lever *c*.

What I claim is:

1. In a door construction, comprising upper and lower separable door sections and an inside latch lever for the lower door section yieldingly forced to one end of its swinging arc, the combination of a stop adjacent such end of the swinging arc of the 10 latch lever, and a device secured to the upper door section and comprising an arbor passing through the upper door section, a handle on the outside end of the arbor, and a lever arm on the inside of the arbor, the 15 end of which is engaged between the latch lever and the stop when the device is inoperative and adapted to contact the latch lever to operate the same when the lever arm is 20 sprung.
- 25 2. In a door construction, comprising upper and lower separable sections and an inside latch lever yieldingly urged toward one end of its swinging arc, the combination of a stop adjacent said end of the latch lever swinging arc, and a device secured to the upper door section, comprising an arbor rotatably held in the upper door section, a handle on the outside end of the arbor and a lever arm on the inside end of the arbor and 30 provided at its extreme end with cushioning 35 means for contacting the stop and the latch

lever when the parts are in inoperative position, said lever arm serving to swing the latch lever when the lever arm is swung.

3. In a door construction, comprising upper and lower separable door sections and a latch lever yieldingly urged toward one end of its swinging arc, the combination of a stop secured adjacent said end of the swinging arc, and a device rotatably mounted in 40 the upper door section, comprising an arbor passing through the upper door section, a handle on the outside end and a two-arm lever secured to the inside end, one arm of which is pinched between the stop and the 45 yieldingly urged latch lever when the parts are inoperative and which serves to actuate the latch lever when the lever arm is swung, and the other arm of which acts as a lever handle on the inside of the door.

4. In a door construction, comprising upper and lower separable sections and a latch lever that is ordinarily yieldingly urged toward one end of its swinging arc, the combination of a stop adjacent the end of said 50 swinging arc, and a device rotatably mounted in the upper door section and comprising an arbor passing through the upper door section, a handle on the outside end, and a lever arm on the inside end of the arbor provided at its extreme end with a rivet-shaped 55 rubber button which contacts with the stop and the latch lever when the parts are in inoperative position.

In testimony whereof, I sign this specification.

JOHN T. ALLMAND
